UNITED STATES PATENT OFFICE.

GEORGE T. BOND, OF HUNTINGTON, WEST VIRGINIA.

BRAKE-SHOE.

1,282,737.

Specification of Letters Patent. Patented Oct. 29, 1918.

Application filed January 19, 1918. Serial No. 212,620.

To all whom it may concern:

Be it known that I, GEORGE T. BOND, a citizen of the United States, residing at Huntington, in the county of Cabell and State of West Virginia, have invented certain new and useful Improvements in Brake-Shoes, of which the following is a specification, reference being had therein to the accompanying drawings.

10 This invention relates particularly to a car brake-shoe of compound type that includes a friction member, which contacts with a wheel-tread, and a holder, which operates with a brake-head to maintain the shoe in operating position.

The invention provides means, as herein-after set forth, whereby the shoe-parts are held together in such manner that they may be disassembled without injury to the 20 holder, threaded fasteners being used for this purpose.

The two members thus associated form a unitary shoe, which is attached to the brake-head in the usual manner of a single-member shoe in general use.

The invention has in view the provision of a brake-shoe that will be more economical in service than a reinforced or backed shoe of the usual form, which has to be removed and entirely scrapped when only a little more than half worn, because of the liability of the wheel wearing through into the brake-head and thereby damaging it. It is to overcome this objection that the holder of 35 the shoe is made detachable, whereby it may be used successively on other friction or wearing members.

Even if a single-member shoe wears away in a uniform manner until the wheel almost 40 comes into contact with the brake-head, there still is a considerable amount of material unworn, because of the attaching and retaining keepers extending into the brake-head.

45 With this invention, the keepers form an integral part of the holder, the concave surface of which is equi-distant from the wheel-tread, so that, if the friction member wears away uniformly, there will be practically no 50 unworn material remaining in the friction member. Thus, after wear and removal from a brake-head of a shoe formed in accordance with this invention, the holding member can be detached from the friction 55 member, attached to a new friction mem-

ber, and the shoe thus formed placed in service.

Another object of the invention is that, by interposition of the holder between the friction member and brake-head, the head 60 will be protected from wear by the holder even if the friction member is worn entirely away and friction is taken by the holder, for the latter is less expensive of replacement than the brake-head.

65 The brake-shoe provided by the invention is simple to manufacture, its parts can be assembled quickly and easily and without the necessity of employing special tools, and the cast friction or wearing member can be 70 cleaned of adhering mold-sand and handled and transported without liability of damage of its parts.

When read in connection with the description herein, the features of the invention will 75 be apparent from the accompanying drawings, forming part hereof, wherein embodiments of the invention are disclosed, for purposes of illustration.

80 While the disclosures herein now are considered to exemplify preferable embodiments of the invention, it is to be understood that it is not the intention to be limited necessarily thereto in interpretation of the claims, as alterations within the limits of 85 the claims can be made without departing from the nature and spirit of the invention.

Like reference-characters refer to corresponding parts in the views of the drawings, of which—

90 Figure 1 is a side elevation, partly in section, of a brake-shoe having a plurality of keepers, assembled and attached to a brake-head;

Fig. 2 is a plan view, showing in part the holding member and in part the wearing member;

Fig. 3 is a transverse section on the line III—III, Fig. 1.

Fig. 4 is a detail longitudinal sectional view on the line IV—IV, Fig. 2, illustrative of a method of locking an attaching-screw in place;

Fig. 5 is a fragmentary plan view, illustrative of the screw-locking arrangement;

Fig. 6 is a fragmentary longitudinal sectional view of the wearing member, illustrative of an alternative form of screw-threads therein;

Fig. 7 is a side elevation, partly in sec-

tion, showing an alternative arrangement of securing to the wearing member a holder having a single keeper adapted to be used with a standard brake-head;

5 Fig. 8 is a plan view of the form of shoe disclosed by Fig. 7, the holder being partly broken away to show part of the wearing member;

10 Fig. 9 is a transverse sectional view on the line IX—IX, Fig. 7;

Fig. 10 is a side elevation, partly in section, of another form adapted for use with a standard brake-head, showing the holder held by bolts in association with the wearing member;

15 Fig. 11 is a plan view, showing in part the holder and in part the friction member of the form disclosed by Fig. 10;

20 Fig. 12 is a fragmentary longitudinal sectional view on the line XIII—XII, Fig. 11;

Fig. 13 is a view of a modification of bolt arrangement; and

25 Fig. 14 is a sectional view on the line XIV—XIV, Fig. 13.

30 In all of the views in which those parts appear, 1 designates a brake-head, 2 designates one or more recesses or seats or mortises formed therein for reception of a corresponding number of similarly shaped 35 keepers 3 of a malleable or otherwise suitably formed brake-shoe back or holder 4 secured to a wearing member 5, and 6 designates a retaining-key disposed in longitudinal openings 7 in the brake-head and 8 in 40 the keepers, the key and keepers maintaining the shoe on the head in a manner well known to the art.

45 In order that a worn wearing member may be removed from a holder and the latter again used in association with a new wearing member, the invention contemplates the employment of threaded fasteners, for holding the parts together, which are disposed through the holder and have removable engagement in the wearing member.

50 The fasteners are disposed through and are rotatable in openings 9 in the holder, these openings being slightly elongated or elliptical to allow for variation in the location of screw-threads in recesses or seats 10 in the wearing member into which the fastenings extend. In all forms, except that shown by Fig. 6, the recesses or seats 10 are slightly larger than the portions of the 55 fasteners disposed therein, and the threads for engagement with the fasteners are formed in material that is embedded in the wearing member at the time of casting thereof, the cutting of the threads preferably being done prior to the casting operation.

55 In the forms illustrated by Figs. 1, 2, 3, 4, and 13, the screw-threads for the recesses or seats 10 are formed in nuts or the like 11, 60 one for each fastener, each of them is of

greater area in plan than the recess or seat, and it is embedded in the wearing member at a place removed from the rear face thereof at the time of casting and it spans the recess or seat. As the nuts are a distance 70 from the open ends of the recesses or seats, the threads thereof are less liable to injury while the wearing members are being cleaned, handled, and transported prior to attachment to the backs.

75 In the case of a form of shoe such as illustrated by Fig. 1, wherein a malleable steel back or holder is formed with a plurality of keepers 3 of a number corresponding to that of the seats or mortises 2 in the head, 80 the portions of the back that contact with the wearing member at the ends and between the keepers have the openings 9 countersunk, there being a pair of such openings in each abutting portion and each opening of a 85 pair being located adjacent to a side edge of the back. The back or holder and wearing member are held together by screws 12, the heads 13 of which are seated in the countersunk openings 9 and the threaded shanks 14 90 of which engage in the embedded threaded members 11.

95 In order to relieve the fasteners of the shearing stresses imposed upon the wearing member by contact of the thread of a moving wheel, each abutting portion of the back or holder is formed between the screws with an opening 15, which takes a correspondingly-positioned protuberance 16 of the wearing member.

100 When a shoe with parts assembled as described is placed on a brake-head such as shown by Fig. 1, the portions of the head outside of and between its seats or mortises abut the portions of the back through which the screws are disposed and liability of the screws working out of threaded engagement in the wearing member and loss of that member are lessened. However, in order 105 more reliably to prevent rotary movement 110 of the screws, both before and after the shoe is placed on the head, each of the countersunk openings 9 of the back or holder is formed with a slot 17, as seen clearly in Figs. 4 and 5, and after the screws are set up a portion of the head of each is spread or upset into the slot, as seen in Fig. 4, and the fasteners thereby locked. The fasteners so locked may be turned out, when it is desired to separate the holder and wearing 115 member, by suitable tools able to overcome the locking action.

120 If desired, the threads for engagement of the threaded fasteners may be formed directly in the material of the wearing member, as shown at 18 in Fig. 6, instead of being formed in material different from the wearing member. In this case, the back-abutting face of the wearing member is 125 counter-sunk or formed with a depression at 130

the openings to the threaded recesses, as shown at 19, in order that the threads, as in the other forms, may commence at a place away from the face and thereby be less liable to injury before insertion of the fasteners.

There is not so much necessity of internally reinforcing a wearing member of the type exemplified by Fig. 1 as in the case 10 of a form having a single keeper, because the plurality of keepers operate to retain all of the shoe on the brake-head after fracture between the holding-points, as sometimes occurs. With a single-keeper shoe, in 15 order to deter fracture, to aid the back in holding the parts together in case of fracture, and at the same time to provide material different from the wearing member to carry threads for engagement with the fasteners, strips 20 are disposed longitudinally 20 of and are embedded in that member at the time of casting. Although shown only in a shoe of the single-keeper type for a standard head, the strips, of course, may be used 25 in a multiple-keeper shoe such as shown by Fig. 1.

Usually two such strips are provided in a wearing member, and each is positioned comparatively near a side edge of the member 30 outside of the protuberances 21 located at the end portions of the member to seat in depressions in the brake-head to relieve the keeper of some strain; as shown by Figs. 7, 8, 9, 10, 11, and 12.

35 The recesses or seats 10 of the form shown by Figs. 7, 8, and 9 are arranged in alignment with the strips and are spanned thereby, and a pair thereof is positioned at places corresponding to the points of contact with the holder 4. In this form, the screws 12 extend through the holder into engagement with threads in the strips, there is little liability of their working out because of contact of the brake-head against 40 the heads of the screws, as a further precaution against loosening of the screws they are locked by upsetting the heads into slots, and protuberances 16 of the wearing member extend into openings 15 of the holder 45 for the purpose of relieving the latter of shearing stresses, as in the case of the previously-described form.

The invention further contemplates the employment of a bolt or lag-screw type of 50 fastener to maintain the holder in association with the wearing member, as illustrated by Figs. 10, 11, 12, 13, and 14, and this type of fastener is particularly adapted for use with a shoe for service on a standard brake-head; which takes a single keeper and which is recessed on each side of the keeper-recess (as shown at 1^a in Fig. 10), as the recesses 55 accommodate the heads of the fasteners.

Having reference to Figs. 10 and 11, bolts 60 22 extend through the holding member (at

places where the latter is not contacted by the head) into the recesses 10 of the wearing member, wherein they engage threads in the strips 20. Usually there are two such fasteners at each side of the keeper, and 70 those of each pair are disposed in lines oblique to the axis of the wearing member in order that the places of attachment may be more diversified than if the location were in a transverse line. In order to prevent 75 the bolts from working loose, in each pair a locking-strip 23 extends from one to the other and under the heads thereof, and it is of bendable metal so that a portion may be bent upwardly against the sides of the 80 head and thereby lock the bolts.

Although the bolt or lag-screw type of fastener is particularly adapted to a shoe for service on a standard brake-head, it also is susceptible of use in a multiple-keeper 85 shoe, as exemplified by Figs. 13 and 14, which show one of the contact-points of the head and shoe-back or holder. In such a case, the brake-head is formed in each contact portion with a transverse slot 24, bolts 90 22^a are used in place of the screws shown by Fig. 1, the heads thereof pass into the slots during the lateral movement of placing the shoe on the head, and the walls of the slots by contact with the sides of the 95 bolt-heads prevent the fasteners from working loose. Preferably the bolts have oblong heads to make the locking action more reliable.

In order that the body of the wearing 100 member may be worn away almost entirely prior to reaching points of contact with the back or holder, and thus to decrease the liability of injury to that member and the head, protuberances or raised portions on 105 the wearing member contact with the holder and maintain it slightly removed from the body, these protuberances being designated by 25 in Figs. 1, 2, 4, 5, 6, 7, 8, 10, 11, and 13, and they also being in the form of bosses 110 26 surrounding the openings of the recesses 10 for the bolts 22 as seen in Figs. 10 and 11.

It will be seen that in all of the forms of wearing member herein disclosed the threads for engagement with the back or 115 holder fasteners are a distance from the open ends of the recesses or seats, and, therefore, are not liable to injury during cleaning, handling, transportation, etc.; that the several forms of fasteners are such 120 that the backs or holders may be secured to and removed from the wearing members without the necessity of employing special tools; and that reliable means are provided to prevent the loosening of the fasteners 125 while in service. Further, the wearing member has no fixed projecting parts permanently projecting that are liable to damage during the period between fabrication and attachment to a holder.

Having thus described my invention, what I claim as new, and desire to secure by Letters' Patent, is—

1. In a brake-shoe, a holder having a keeper arranged to coöperate with a brake-head and formed with fastener-openings, a wearing member abutting said holder formed with threaded ways, and threaded fasteners rotatable in said holder-openings and engaging in said threaded ways whereby said parts are detachably held together. 5
  2. In a brake-shoe, a holder having a keeper arranged to coöperate with a brake-head and formed with fastener-openings, a wearing member abutting said holder having ways formed with threads commencing at points removed from the openings thereof, and threaded fasteners rotatable in said holder-openings and engaging in said threaded ways whereby said parts are detachably held together. 10
  3. In a broke-shoe, a holder having a keeper arranged to coöperate with a brake-head and formed with fastener-openings, a wearing member abutting said holder formed with threaded ways, threaded fasteners rotatable in said holder-openings and engaging said threaded ways whereby said parts are detachably held together, and means whereby said fasteners are locked 25 against rotation. 30
  4. In a brake-shoe, a holder having a keeper arranged to coöperate with a brake-head and brake-head contact-points at other places formed with fastener-openings, a wearing member abutting said holder formed with threaded ways, and threaded fasteners rotatable in said holder-openings and engaging said threaded ways whereby 35 said parts are detachably held together. 40
  5. In a brake-shoe, a holder having a keeper arranged to coöperate with a brake-head and formed with fastener-openings, a wearing member abutting said holder 45 formed with ways, members embedded in said wearing member and spanning said ways below the holder-contacting points and having threaded openings in said ways, and threaded fasteners rotatable in said holder- 50 openings and engaging in said threaded openings whereby said parts are detachably held together. 55
  6. In a brake-shoe, a holder having a keeper arranged to coöperate with a brake-head and formed with fastener-openings, a wearing member abutting said holder formed with a series of ways, a reinforcing-strip embedded in said wearing member and spanning said ways below the holder-contacting points and having threaded openings in said ways, and threaded fasteners rotatable in said holder-openings and engaging in said threaded openings whereby 60 said parts are detachably held together. 65
  7. A wearing member for brake-shoes having ways opening to its rear face formed with threads commencing at points removed from the open ends thereof arranged to receive fasteners for its attachment to a holder. 70
  8. A wearing member for brake-shoes having ways, and members embedded therein spanning said ways below the rear face thereof and having threaded openings in said ways arranged to receive fasteners for attachment of the wearing member to a holder. 75
  9. A wearing member for brake-shoes having a series of ways, a reinforcing member embedded therein spanning said ways and having threaded openings in said ways arranged to receive fasteners for attachment of the wearing member to a holder. 80
  10. In a brake-shoe, a wearing member having protuberances on its rear face and threaded ways in said protuberances, a holder having a keeper arranged to coöperate with a brake-head and formed with fastener-openings, and threaded fasteners rotatable in said holder-openings and engaging in said threaded ways and maintaining said holder to said wearing member in abutment with said protuberances. 85
  11. In a brake-shoe, a wearing member having protuberances on its rear face, and a holder having a keeper arranged to coöperate with a brake-head and detachably secured to said wearing member with a face in abutment with said protuberances and thereby maintained slightly removed from the body proper of the wearing member. 90
- In witness whereof I have affixed my signature. 100

GEORGE T. BOND.
